[57] CLAIM

The ornamental design of a combined ceiling fan and light fixture, as shown and described.

DESCRIPTION

FIG. 1 is a bottom perspective view of a combined ceiling fan and light fixture showing my new design; FIG. 2 is a fragmentary top plan view thereof; FIG. 3 is a fragmentary side elevational view thereof, the sides opposite and adjacent being substantially similar in appearance; FIG. 4 is a fragmentary bottom plan view thereof; FIG. 5 is a fragmentary bottom perspective view of an alternate embodiment thereof; FIG. 6 is a fragmentary side elevational view of the embodiment of FIG. 5, the sides opposite and adjacent being substantially similar in appearance; and FIG. 7 is a fragmentary bottom plan view of the embodiment of FIG. 5. The blade portions in FIGS. 2-7 have been shown broken-away for convenience of illustration.
